UNITED STATES PATENT OFFICE.

HERBERT J. HAWTHORNE, GUY B. WYATT, AND OTTO P. WARNER, OF CLEVELAND,
OHIO; SAID WARNER ASSIGNOR TO R. H. REYNOLDS, OF MILWAUKEE, WISCONSIN.

AIR-PUMP.

1,021,310.

Specification of Letters Patent. Patented Mar. 26, 1912.

Application filed March 6, 1911. Serial No. 612,659.

To all whom it may concern:

Be it known that we, HERBERT J. HAWTHORNE, GUY B. WYATT, and OTTO P. WARNER, citizens of the United States, residents of Cleveland, county of Cuyahoga, and State of Ohio, have invented a new and useful Improvement in Air-Pumps, of which the following is a specification, the principle of the invention being herein explained and the best mode in which we have contemplated applying that principle, so as to distinguish it from other inventions.

Our invention relates to an air pump, and more especially to such as employ single-acting pistons.

The object of the invention as fulfilled by novel changes in the relative position of diverse parts is to effect an increased general efficiency.

20 The said invention consists of means which are hereinafter fully described and particularly set forth in the claims.

25 The annexed drawing and the following description set forth in detail certain means embodying our invention, the disclosed means, however, constituting but one of various mechanical forms in which the principle of the invention may be applied.

30 In said annexed drawing:—Figure 1 is a vertical section of a machine embodying my invention, and showing driving means in simple outline. Fig. 2 is a similar section on line II—II of Fig. 1.

35 A hollow air-tight base A having a pipe outlet a' supports the upright frame B. This latter comprises preferably an integral cylinder b' interiorly adjacent a flange b^2 by means of which it is attached to the base A, as clearly shown in Fig. 1. This cylinder has its lower end b^3 open and somewhat above its lower extremity b^4 is provided with a plurality of side-outlet openings b^5 . A movable cylinder head C constructed as shown, is adapted to inclose the lower end b^3 including the openings b^5 within its annular recess c' and necessarily with the air-tight connection afforded by the piston rings b^6 which are located just above the openings b^5 . The arrangement is such that the cylinder head C is normally held in close engagement with the lower extremity b^4 and in this position it closes the openings b^5 both interiorly and exteriorly as will be apparent from an inspection of Figs. 1 and 2. The upright spring c^2 ex-

tending into the angular centrally disposed depression c^3 serves to maintain this normal engagement, as will be readily understood.

The upper portion of the frame is made to flare outwardly in three directions, as 60 represented in Fig. 2, leaving one open side whereby a hollow open compartment b^7 laterally of approximate circular cross-section is provided. The open side is supplied with a removable cover plate b^8 , for the obvious 65 purpose of permitting access to the interior. An integral centrally disposed bearing b^9 is further provided to accommodate the crank-shaft D, which in turn supports a driving gear E. A connecting rod F establishes an operative relation between the shaft D and a piston G. The gear E may be driven by a pinion H as mounted upon the driving shaft J of an electric motor, 70 shown in outline in Fig. 1.

75 A plurality of adjustably controlled air inlets K are arranged to communicate directly with the cylinder b' , and in accordance with our conception at points variously located intermediately of the ends of the 80 strokes of the piston, the precise arrangement being such that the communication between some of the several inlets and the cylinder, whether simultaneous or successive, is positively assured considerably prior 85 to the arrival of the piston at dead center, which is generally midway of the length of the cylinder. By thus positioning the means for replenishing the air supply in the cylinder, more remotely from the end of the 90 return than from the end of the compression stroke of the piston, it becomes possible to have the inlets disposed at different points therealong, whereby they may serve 95 as successively operating relief valves for the purpose, in turn, of having the vacuum created behind the piston taken care of gradually, and an equal pressure maintained throughout the return stroke of the piston. This is calculated to insure that uniform 100 load which is so prominent a requisite to general efficiency.

105 Our air pump in the nature of a self-contained structure, is calculated to operate in the following manner: The reciprocation of the piston G through the medium of the operating mechanism first alternately compresses the air in the cylinder and drives it out through the openings b^5 against the action of the cylinder head, as will be mani- 110

fest. During this alternate up and down movement of the cylinder head C, an air cushioning effect is established between it and the inclosed portion of the cylinder, 5 whereby a substantially noiseless valve structure is attained. The hollow air-tight base meanwhile constitutes an air receiver from which the air under compression may be more uniformly withdrawn by reason of 10 being partially independent of the intermittent discharges from the cylinder. This should carry quite an appreciable value where, for example, it is intended to inflate the rubber tires on automobiles. During the 15 return stroke of the piston, the properly adjusted inlet valves will very gradually overcome the vacuum so that at the end of the stroke none at all remains, and hence the jolting at present resulting from the sudden 20 inrush at the end of each alternate stroke is positively precluded.

Having fully described our invention, what we claim and desire to secure by Letters Patent is:—

25 1. An air pump comprising a cylinder having one end open and provided adjacent thereto with a lateral opening, a piston within said cylinder, operating mechanism connected with said piston, and a movable cylinder-head provided with an annular recess adapted to inclose said end and opening.

30 2. An air pump comprising a cylinder having near one end a plurality of circumferentially disposed openings, a piston within 35 said cylinder, operating mechanism connected with said piston, and a movable cylinder-head adapted to both interiorly and exteriorly close said openings.

3. An air pump comprising a frame hav-

ing a hollow member, a cylinder having an 40 open end extending into said member, and provided with an inlet and a side outlet, the latter communicating with said hollow member, a movable cylinder-head provided with a recess adapted to successively close 45 said cylinder end and side outlet, an operating shaft projecting into said frame, a pinion upon said shaft, a driving gear engaging said pinion, a crank-shaft connected with said gear, a connecting rod secured to 50 said crank-shaft, and a piston connected with said rod.

4. An air pump comprising an upright frame having a receiving chamber, a cylinder extending into said chamber and having its inserted end open, a movable cylinder-head having an annular recess for permanently inclosing said open end, an operating shaft projecting into said frame, a pinion upon said shaft, a driving gear engaging 55 said pinion, a crank-shaft connected with said gear, a connecting rod secured to said crank-shaft, and a piston pivotally connected with said rod, said cylinder being provided with an air inlet more remotely located from the end of the return than from the end of the compression stroke of said piston, and an air outlet within said chamber located near said open end, and adapted to be closed by said cylinder head. 70

Signed by us, this 28th day of February, 1911.
